CLAIM

The ornamental design for an utensil organizer, as shown and described.

DESCRIPTION

FIG. 1 is a perspective view of an utensil organizer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the utensil organizer;

FIG. 10 is another exploded perspective view thereof; and,

FIG. 11 is an exploded top plan view thereof.

The broken lines in the drawings depict portions of the utensil organizer that form no part of the claimed design.

1 Claim, 11 Drawing Sheets
